UNITED STATES PATENT OFFICE

WILLIAM H. JAEGER, OF TRENTON, NEW JERSEY

DEVELOPING APPARATUS

Application filed January 5, 1929. Serial No. 330,665.

This invention relates to a developing apparatus and has relation more particularly to a device of this kind especially designed and adapted for use in connection with direct positive print paper, and it is an object of the invention to provide an apparatus of this kind wherein the paper to be developed is carried in succession through various requisite baths and in a manner to eliminate the liability of scratching or otherwise marring the emulsion.

The invention consists in the details of construction and in the combination and arrangement of the several parts of my improved developing apparatus whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawings, wherein:

Figure 1 is a vertical longitudinal sectional view taken through an apparatus constructed in accordance with an embodiment of my invention;

Figure 2 is a sectional view taken substantially on the line 2—2 of Figure 1;

Figure 3 is an enlarged fragmentary view illustrating one of the carrying rollers and the trackway associated therewith;

Figure 4 is a fragmentary view in top plan of the roller at the delivery end of the apparatus.

As herein disclosed, my improved apparatus comprises a tank T of requisite dimensions and which has its lower portion divided at spaced points lengthwise thereof by the partitions 1 into the chambers 2, 3, 4, 5, 6, 7, 8 and 9. The chambers 3, 5, 7 and 9 are adapted to contain water.

The chamber 2 is to contain a supply of developer, the chamber 4 a supply of bleach, the chamber 6 a supply of clear, and the chamber 8 a supply of redeveloper.

The developer solution preferably com-

prises the following admixture diluted to 160 oz.:

	Oz.
Hydroquinone	4
Sulphite of soda (anhy.)	8
Boric acid (H_3Bo_3)	1
Bromide of potassium	1/2
Caustic soda (sticks)	4

This developer solution is used full strength and at a temperature ranging from 65° and 75° F., the time of development being approximately forty-five seconds.

The bleach comprises a solution diluted to 160 oz. of

	Oz.
Potassium bichromate	1.5
Sulphuric acid	2.0

This solution is also used full strength at a temperature between 60° and 75° F.

The clear comprises an admixture of

	Lb.
Sodium sulphite (anhy.)	1

This is used full strength at a temperature between 60° and 75° F.

The redeveloper comprises the following ingredients diluted to 160 oz.:

	Oz.
Hydroquinone	4
Sulphite of soda (anhy.)	8
Boric acid	1
Bromide of potassium	1/2
Caustic soda	4

This redeveloper is to be used full strength and also at a temperature between 60° and 75° F.

The partitions 1 terminate a desired distance below the top of the tank T and support the parallel members 10 which provide mountings for the shafts 11 which are further supported by the side walls of the tank T. Each shaft 11 has mounted thereon between the members 10 a carrier roller C comprising two side discs 12 connected by the interposed cross members 14. Each of the discs 12 at the transverse center of its periphery is provided therearound with a plurality of circumferentially spaced outstanding teeth 15 which are adapted to engage within the marginal perforations 16 provided in the film strip 17 to be developed.

The developer solution preferably com-

The discs 12 of the rollers C associated with the chambers 3, 5, 7 and 9 are herein disclosed as of a diameter smaller than that of the discs 12 of the remaining rollers, but all of the discs are caused to rotate at the same peripheral speed by a worm drive connection 18 between each of the shafts 11 and a drive shaft 19 disposed along a side wall of the tank T.

10 Positioned immediately below each of the discs 12 and carried by a member 10 is a curved film guide 20 conforming to the adjacent portion of said disc 12 and which is arranged outwardly of the teeth 15. Interposed between adjacent longitudinally spaced discs 12 and bridging the space therebetween are the upwardly curved guide members 21 also carried by a member 10. With the various rollers C in operation a film to be 15 treated is operatively engaged with the first roller C and the same will be carried through the upper portion of the developer chamber 2 and said film will be effectively maintained in requisite engagement with said roller by 20 the associated guides 20, the position or location of such guides 20 leaving the intermediate or exposed portion of the film free of contact. This is true in connection with all of the rollers, and as the film passes upwardly with one roller it is caused to have proper engagement with the adjacent roller of the intermediate guide members 21. When the film reaches the roller at the discharge end of the tank, the film is prevented 25 from passing around such roller by the guide fork 22 carried by each of the members 10 and having close contact with the periphery of a disc 12 at opposite sides of the teeth 15 thereof.

40 My improved tank is especially adapted for use in connection with direct positive print paper and the speed of travel of the film through the tank is such to have the requisite development completed when the 45 film is discharged therefrom.

It is believed to be obvious that the water within the chambers 3, 5, 7 and 9 serves to wash the film after each separate treatment incident to its development.

50 From the foregoing description it is thought to be obvious that a developing apparatus constructed in accordance with my invention is particularly well adapted for use by reason of the convenience and facility with which it may be assembled and operated, and it will also be obvious that my invention is susceptible of some change and modification without departing from the principles and 55 spirit thereof and for this reason I do not wish to be understood as limiting myself to the precise arrangement and formation of the several parts herein shown in carrying out my invention in practice except as hereinafter 65 claimed.

I claim:—

1. A tank for the development of direct positive print paper divided into a plurality of chambers, each containing a liquid incident to the development of the paper, spaced discs rotatably supported above each of the chambers and extending downwardly thereinto, means for driving said discs at the same peripheral speeds, guides associated with the lower portions of the discs to maintain the paper in proper position with respect to the discs, said discs having outstanding teeth for engagement with perforations in the paper, the guides being positioned outwardly of the teeth and engaging the marginal portions of said paper. ⁷⁵

2. A tank for the development of direct positive print paper divided into a plurality of chambers, each containing a liquid incident to the development of the paper, spaced discs rotatably supported above each of the chambers and extending downwardly thereinto, means for driving said discs at the same peripheral speeds, guides associated with the lower portions of the discs to maintain the paper in proper position with respect to the discs, said discs having outstanding teeth for engagement with perforations in the paper, the guides being positioned outwardly of the teeth whereby to engage the marginal portions of the paper, and guides bridging the space between adjacent discs to cause the paper to properly pass from one disc to another. ⁸⁰

3. A tank for the development of direct positive print paper divided into a plurality of chambers, each containing a liquid incident to the development of the paper, spaced discs rotatably supported above each of the chambers and extending downwardly thereinto, means for driving said discs at the same peripheral speeds, guides associated with the lower portions of the discs to maintain the paper in proper position with respect to the discs, said discs having outstanding teeth for engagement with perforations in the paper, the guides being positioned outwardly of the teeth whereby to engage the marginal portions of the paper, and a fork coacting with each of the discs at the discharge end of the tank to prevent the film continuing around said disc, each of said forks straddling the teeth of the associated disc. ¹⁰⁵

110 In testimony whereof I hereunto affix my signature. ¹¹⁵

WILLIAM H. JAEGER. ¹²⁰
